ROOM DEODORANT VAPORIZING CASING

Joseph A. Hill, Glen Ellyn, Ill., assignor to
Lien Chemical Company, Franklin Park, Ill.

Filed June 10, 1971, Ser. No. 152,024

Term of patent 14 years

Int. Cl. D23—99

U.S. Cl. D23—148

Fig. 7.

Fig. 8.

FIG. 1 is a side elevational view of a room deodorant vaporizing casing, embodying my new design;

FIG. 2 is a rear elevational view thereof;

FIG. 3 is a top plan view thereof;

FIG. 4 is a bottom plan view thereof on a reduced scale;

FIG. 5 is a side elevational view thereof with the rear panel in an opened position and the casing broken away at the bottom for purposes of disclosure;

FIG. 6 is a front elevational view thereof on a reduced scale;

FIG. 7 is a front perspective view thereof taken from above the casing being broken away for convenience of illustration;

FIG. 8 is an inverted bottom perspective view thereof.

I claim:

The ornamental design for a room deodorant vaporizing casing, substantially as shown and described.
